NURSING BOTTLE HOLDER

Michael Rayko, Indiana, Pa.

Application July 2, 1946, Serial No. 681,060

3 Claims. (Cl. 248—105)

1

This invention relates to a novel and improved holder for baby nursing bottles, the primary object of the invention being to provide a holder so constructed as to eliminate the danger of shaking of the baby which is incident to other holders which retain the nipple in the baby's mouth after feeding has ceased.

Another important object of this invention is to provide a nursing bottle holder wherein means is provided to hold the bottle flexibly in such a manner that when the baby stops feeding and releases the nipple of the bottle, the bottle will swing so as to carry the nipple upwardly out of the baby's mouth, yet within reach of the baby's hand so that he can resume feeding when so inclined.

A further important object of this invention is to provide a nursing bottle holder of the character indicated above which securely and comfortably supports the bottle in the proper position in the crib close to the shoulders of the reclining infant, and which is composed of a minimum of simple and inexpensive parts.

Other important objects and advantageous features of this invention will be apparent from the following detailed description and accompanying drawing, wherein a specific but non-limitative embodiment of the invention is set forth merely for purposes of illustration.

In the drawing:

Figure 1 is a side elevation, showing the bottle tilted in feeding position in full lines, and in released tilted position in dotted lines.

Figure 2 is a transverse vertical section taken on the line 2—2 of Figure 3, and

Figure 3 is a left hand end or front elevation of Figure 2.

Referring to the drawing in detail, the herein illustrated embodiment of the invention comprises a frame comprising a pair of similar inverted T-shaped sides 4 and 5 which may be made of wood, plastic or metal, with one arm of the cross head 6 elongated as indicated at 7. The sides 4 and 5 are flat and relatively thin and have their edges rounded as indicated at 8, and their terminal ends semi-circular in shape as indicated at 9, 10 and 11, respectively, so that all possibly harsh points of contact with the baby or his crib or the coverings thereon are eliminated.

The straight lower edges 12 are designed to rest upon the supporting surface of the crib (not shown), with the uprights 13 of the sides projecting straight upwardly in substantially perpendicular planes.

The sides 4 and 5 are secured rigidly together

2

parallel to each other to rest upon the crib on opposite sides of the baby, by means of a cross member 14 which has depending concaved legs 15 secured by means of screws or the like 16 to the inner surfaces of the uprights 13 below the upper ends 11 thereof.

The bottle holding member comprises a rectangular or other suitable cross section bar 17 parallelly spaced above the cross member 14 between the upper ends of the frame side uprights 13 and rockably supported on its longitudinal axis by pivot screws or the like 18 mounted in said uprights, said bar being sufficiently wide at its middle to provide a firm rest for the nursing bottle 19.

15 A rubber or other suitable material bottle holding strap 20, or other suitable equivalent, has its ends secured at 21 to the top of the bar 17 so that when the bottle 19 is pushed through the resulting loop the bottle will be securely held on the bar 17, and will be capable of lengthwise adjustment in accordance with the amount of feeding fluid in the bottle to predetermine the tendency of the bottle to overbalance and return to the retracted position illustrated in dotted lines in 20 Figure 1, when released by the baby during interruptions in or at the end of his feeding.

Retracting helical springs 22 have their upper ends attached at 23 to the back of the ends of the bar 17 and are slanted outwardly and have their lower ends attached at 24 to the legs 15 of the cross member 14, so that when the baby releases the bottle nipple 25, the bottle will be gently but positively swung upwardly, so that the nipple is withdrawn from the baby's mouth and the bottle assumes an out-of-the-way but readily reachable position during an interruption of or at the end of the baby's feeding, so that there is no danger of the nipple gagging or choking the baby.

What is claimed is:

40 1. A holder for a nursing bottle, comprising a frame comprising a pair of sides to rest upon a supporting surface at opposite sides of a baby, a cross member secured to and between upper portions of said sides, forwardly and rearwardly tiltable bottle holding means mounted on and between said sides above said cross member, and spring means normally retracting said bottle holding means into rearwardly tilted position.

2. A holder for a nursing bottle comprising a frame consisting of a pair of sides arranged to rest upon a supporting surface at opposite sides of a baby reclining on such surface, said sides being elongated to extend longitudinally alongside of the baby and having uprights thereon rising therefrom, a cross member secured to and between

upper portions of said uprights and rigidly securing said sides together in substantially parallel relation, bottle holding means comprising a bar pivoted at its ends to and between said uprights above said cross member whereby said bar can tilt forwardly and rearwardly on its longitudinal axis, spring means operating between said frame and said bar and normally rearwardly tilting said bar rearwardly, and bottle securing means on said bar for releasably securing a nursing bottle resting thereon with the nipple of said bottle directed forwardly, said spring means being arranged so as to yield to permit the bottle to assume a forwardly tilted position with the bottle nipple in the mouth of the baby, and to return to a rearwardly tilted position when the nipple is released by the baby.

3. A holder for a nursing bottle comprising a frame consisting of a pair of sides arranged to rest upon a supporting surface at opposite sides of a baby reclining on such surface, said sides being elongated to extend longitudinally alongside of the baby and having uprights thereon rising

therefrom, a cross member secured to and between upper portions of said uprights and rigidly securing said sides together in substantially parallel relation, bottle holding means comprising a bar pivoted at its ends to and between said uprights above said cross member whereby said bar can tilt forwardly and rearwardly on its longitudinal axis, spring means operating between said frame and said bar and normally rearwardly tilting said bar rearwardly, and bottle securing means on said bar for releasably securing a nursing bottle resting thereon with the nipple of said bottle directed forwardly, said spring means being arranged so as to yield to permit the bottle to assume a forwardly tilted position with the bottle nipple in the mouth of the baby, and to return to a rearwardly tilted position when the nipple is released by the baby, said bottle securing means comprising a stretchable strap fastened at its opposite ends to said bar so as to constrict upon a bottle inserted therein and permitting endwise adjustment of the bottle on the said bar.

MICHAEL RAYKO.
